HYDRAULIC MOTOR

Walter Ferris and James K. Douglas, Milwaukee, Wis., assignors to The Oilgear Company, Milwaukee, Wis., a corporation of Wisconsin

Application July 28, 1930. Serial No. 471,254

18 Claims. (Cl. 121—122)

This invention relates to hydraulic motors.

The hydraulic motor to which the invention applies in particular has a ratchet wheel secured upon its power shaft and rotated by two driving arms each of which is connected to a piston and reciprocated thereby, the pistons are arranged in cylinders which are supplied alternately with a driving liquid to advance the arms alternately and thereby impart rotative force to the ratchet wheel, and one driving arm is retracted while the other driving arm is being advanced, such as the motor disclosed in Patent No. 1,845,257 issued February 16, 1932 to Walter Ferris.

An object of the invention is to cause one driving arm to exert a rotative force upon the wheel before the other driving arm ceases to exert a rotative force thereon to thereby obtain a practically uniform rate of rotation from the intermittently acting driving arms.

Another object is to utilize expansive forces existing in one cylinder and driving arm to bring the other driving arm into operation.

Another object is to avoid any lost motion between the driving arm and the ratchet wheel.

Another object is to provide a hydraulic motor which may be driven at extremely slow speeds without any possibility of stopping through failure of its valve gear to function.

Another object is to control the piston movement by means of a hydraulically operated valve and to provide an accumulator for accelerating the operation of the valve.

Another object is to provide a rolling thrust bearing between the driving arm and its piston.

Another object is to eliminate all objectionable noises.

Another object is to provide a hydraulic motor of this character which will operate smoothly and evenly and which is susceptible of close control.

According to the invention, the pressure ends of the cylinders are momentarily in communication with each other and with the pump at the instant that the operative driving arm is about to be retracted so that the pressure in the operative cylinder and the expansive forces built up by that pressure in the cylinder walls, the piping, the driving arm and associated parts assist the pump pressure in advancing the non-operative driving arm, and the driving arms simultaneously exert separate forces upon the ratchet wheel.

The invention further provides a driving arm which, at the end of its return stroke, engages the wheel without impact to rotate the same during its next working stroke, a hydraulic buffer to cushion the fall of the driving arm as it

disengages a tooth of the wheel, a rolling thrust connection between the driving arm and its piston, means for quickly and positively reversing the driving arms, and a valve operating mechanism which is operated by the movement of the driving arm.

A hydraulic motor embodying the invention is illustrated in the accompanying drawings in which the views are as follows:

Fig. 1 is a top plan view with a part of the top cover plate removed.

Fig. 2 is a side view partly in elevation and partly in section.

Fig. 3 is a detail view showing the position occupied by one of the driving arms just after it is fully retracted and before it actuates the valve operating mechanism as shown in Fig. 2.

Fig. 4 is a detail of a buffer.

Fig. 5 is a schematic drawing of the hydraulic circuit.

Fig. 6 is a view similar to Fig. 5 but showing the plunger of the control valve at an intermediate point in its travel at which point the two power cylinders are in communication with each other and with the pump.

Fig. 7 is a detail view somewhat similar to Fig. 3 but showing the driving arm after it has been advanced a short distance and has permitted the pilot valve to close.

Fig. 8 is a detail view showing the driving arm being retracted but before it reaches the position shown in Fig. 3.

The motor is provided with a closed housing 1 which encloses and supports the working parts thereof, a power shaft 2 journaled in bearings 3 carried by the side walls of the housing 1, a ratchet wheel 4 fixed upon the shaft 2, driving arms 5 and 6 for rotating the ratchet wheel 4, hydraulic motors 7 and 8 for operating the arms 5 and 6, and a control valve 9 for controlling the delivery of driving liquid to the motors 7 and 8.

The driving liquid is supplied from a positive displacement pump 10 which is shown attached to the housing 1 and which, preferably, is regulatable to vary the rate of its delivery to thereby vary the speed of the motor. The pump 10 is a well-known type which delivers liquid at a constant volume until its regulating mechanism is adjusted by forces outside of the pump itself.

As such pumps are well known, the pump 10 has not been illustrated nor described in detail herein. A pump which may be employed for this purpose is disclosed in Patent No. 1,753,562 issued April 8, 1930 to John P. Ferris, but the

control valve shown therein is omitted when that pump is employed to operate the present invention.

The teeth of the ratchet wheel 4 are capable of withstanding the thrust of the driving arms 5 and 6 and have arcuate faces which make a rolling contact with the contact faces 11 of the driving arms 5 and 6, thus causing the free or contact ends of the arms 5 and 6 to roll upwardly as the wheel 4 is rotated and thereby eliminate substantially all friction between the arms and the ratchet teeth.

Preferably, the ratchet teeth consist of round bars 12 which are evenly spaced around a circle concentric to the axis of the shaft 2 and divided into two series. The outer ends of each series of bars 12 are anchored in a disk 13 and the inner ends thereof are anchored in a disk 14. The disks 13 and 14 are carried by a hub 15 which is rigidly secured to the shaft 2 or formed integral therewith.

The motors 7 and 8 have the pistons 16 and 17 thereof arranged, respectively, in cylinders 18 and 19 and provided with rods 20 and 21 to which the driving arms 5 and 6 are connected.

Each of the piston rods 20 and 21 is provided at its forward end with a slot 22 to receive the rear end of its associated driving arm which is pivotally secured therein by a pivot 23 and provided upon its rear end with an arcuate contact face 24 to abut a bearing face 25 formed by the bottom of the slot 22.

Each pivot 23 is fixed in the piston rod and extends through a hole 26 which is formed in the end of the driving arm and is larger than the pivot 23 so as to enable the face 24 to bear against the face 25 during the working stroke and, when the forward end of the driving arm is raised by the rolling engagement between its face 11 and one of the bars 12, to enable the arcuate contact face 24 to rock upon the face 25 and thereby eliminate substantially all friction between the same. During this movement, the pin 23 does not engage the side walls of the hole 26.

The bars 12 in one series are engaged in succession by the driving arm 5 and the bars 12 in the other series are engaged in succession by the driving arm 6, the motors 7 and 8 are operated to advance the driving arms alternately, and one driving arm engages a bar 12 and starts applying force thereto before the other arm ceases to apply force to the bar 12 with which it is engaged. Consequently a continuous rotative force is applied to the shaft 2 and each arm falls as soon as it ceases to apply force to the bar 12 with which it is engaged.

The downward movement of the driving arm is limited by a stop 27 which overhangs the face 11 and engages the bar 12 as soon as the face 11 is disengaged therefrom and thereby supports the driving arm as it is being retracted.

In order to cushion the fall of the driving arms and to thereby prevent them from rebounding, each stop 27 is provided with a bore 28 which extends vertically therethrough and constitutes the cylinder of a hydraulic buffer shown in detail in Fig. 4.

The upper end of the bore 28 is closed by a shallow reservoir 29 from which liquid may flow into the bore 28 through a relatively large passageway 30 which extends vertically through the bottom of the reservoir 29 and is controlled by a check valve 31. When the buffer is operated, the check valve 31 closes the passageway 30 and the liquid is expelled from the bore 28 through a relatively

small passageway 32 which extends through the bottom of the reservoir 29.

The bore 28 has a plunger 33 fitted therein and urged downward by a helical compression spring 34, and the lower ends of both the bore 80 and the plunger are reduced in diameter to limit the downward movement of the plunger.

When the forward end of the driving arm falls, the plunger 33 strikes the bar 12 which has just been disengaged from the face 11. The impact forces the plunger 33 into the bore 28 and tends to eject liquid through the passageway 30 but the check valve 31 closes and the liquid is ejected through the small passageway 32, thereby cushioning the driving arm and preventing it from rebounding.

The spring 34 is employed to insure that the plunger 33 returns to its initial position after it and the bar 12 have moved out of engagement with each other. The strength of the spring 34 95 is small relatively to the force developed by the falling arm so that the fall of the arm is cushioned almost exclusively by the liquid in the cylinder 28.

The rearward movement of the driving arm 100 and the rotation of the ratchet wheel carries the bar 12, which has just been disengaged from the face 11, along the underside of the stop 27 until a face 35, which is formed on the underside of the driving arm and joined to the face 11 by a 105 face 36, is engaged by the next bar in that series which in turn supports the forward end of the driving arm.

Continued rearward movement of the free driving arm and continued rotation of the ratchet 110 wheel causes the bar 12 to move forwardly along the face 35 until it engages the face 36 and then the weight of the driving arm causes the face 11 to ride downwardly upon the arcuate face of the bar 12 and produce a wedging action which moves 115 the face 24 against the face 25 without appreciable impact.

This wedging action is maintained during the entire descent of the free driving arm, which coincides with the extreme end of the working 120 stroke of the engaged driving arm, and is a critical period during which, according to the invention, the load is first divided between the driving arms and then transferred entirely from one to the other without shock and without visible change in speed of rotation of ratchet wheel.

To effect this continuous wedging action, the arcuate face 11 is formed with a radius centering in a point 37 so located that the length of the driving arm between the face 11 abutting against a bar 12 and the face 24 abutting against face 25 will gradually increase as the face 11 slides downwardly in contact with the bar 12 during the descent of the driving arm.

Liquid from the pump 10 is directed to the two 135 motors 7 and 8 alternately by the control valve 9 which has a plunger 38 fitted in its cylinder 39 and provided with two pistons 40 and 41 for controlling two ports 42 and 43, respectively. The port 42 is connected by a duct 44 to the rear 140 end of the motor cylinder 18, the port 43 is connected by a duct 45 to the rear end of the motor cylinder 19, and a port 46 arranged intermediate the ports 42 and 43 is connected by a pipe 47 to the discharge outlet of the pump 10.

Liquid is returned to the pump 10 through the ducts 44 and 45, the control valve 9 and a return pipe 48 which has one end connected to the reservoir of the pump 10 and its other end divided into two branches and connected to two cham-

bers 49 and 50 arranged in the ends of the valve cylinder 39.

The valve plunger 38 is reciprocated by two pistons 51 and 52 which are arranged, respectively, in cylinders 53 and 54 connected to the ends of the valve cylinder 39.

The pistons 51 and 52 are actuated by liquid supplied from a low pressure pump 55, shown diagrammatically as being a gear pump, which is ordinarily incorporated in the pump 10 to supercharge the same, as disclosed in Patent No. 1,753,562 referred to above. The pumps 10 and 55 are protected, respectively, by a high pressure relief valve 56 and a low pressure relief valve 57 which, ordinarily, are also incorporated in the pump 10 as regular parts thereof.

The delivery of liquid from the gear pump 55 to the cylinders 53 and 54 is controlled by two pilot valves 58 and 59 which are arranged immediately below the motors 7 and 8 respectively.

Each of the pilot valves 58 and 59 has a plunger 60 arranged in its casing to control communication between two ports 61 and 62 and between the port 61 and a drain pipe 63 which connects the rear end of each pilot valve to the return pipe 48. The ports 62 of both pilot valves are connected by a pipe 64 to the gear pump 55, the port 61 of the valve 58 is connected by a pipe 65 to the cylinder 54, and the port 61 of the valve 59 is connected by a pipe 66 to the cylinder 53.

Each of the valves 58 and 59 has a helical compression spring 67 arranged therein which urges the plunger 60 forwardly to close communication between the ports 61 and 62 and to open communication between the port 61 and the drain pipe 63.

The plunger 60 of the valve 59 is adapted to be forced rearward against the action of the spring 67, to open communication between the ports 61 and 62 and to close communication between the port 61 and the drain pipe 63, by the lower end of an actuating lever 68 which is pivoted intermediate its ends to the driving arm 6.

The lower end of the lever 68 is urged rearward by a tension spring 69 which has one end attached to the driving arm 6 and its other end attached to the upper end of the lever 68.

As the driving arm approaches the limit of its rearward stroke, a projection 70 on the lower end of the lever 68 engages an abutment 71 which is pivoted to the end of the cylinder 19 and is free to swing forward but is held against swinging rearward. The lower end of the lever 68 is thus held temporarily against further rearward movement, and continued retraction of the driving arm 6 causes the lever 68 to swing upon its pivot against the action of the spring 69 as shown in Fig. 3.

After the piston 17 has stalled at the end of its rearward stroke and when the face 11 on the driving arm 6 has moved downward across the face of the bar 12 a predetermined distance, the projection 70 passes out of engagement with the abutment 71 and the spring 69 swings the lever 68 upon its pivot and forces the plunger 60 rearward against the resistance of the spring 67 as shown in Fig. 2. The rearward movement of the lower end of the lever 68 is limited by an adjustable stop 72 which is carried by the arm 6 to engage the upper end of the lever 68.

As the pilot valve 58 is operated in exactly the same manner and by mechanism identical to that just described, the corresponding parts of

the two mechanisms have been indicated by the same reference numerals.

In order that an adequate supply of liquid may be available at all times for operating the valve 9 with the requisite promptness to insure quick reversals at a uniform speed regardless of changes in rate of movement of the valve gear parts, an accumulator 73 is connected into the supply pipe 64, and the gear pump 55 delivers liquid thereto which depresses its piston 74 against the action of a spring 75, thus storing a quantity of liquid at gear pump pressure to supplement the volume of liquid delivered by the gear pump and providing a reservoir of energy sufficient to move the valve plunger 38 uniformly under all conditions. Liquid which may leak past the piston 74 is returned to the pump 10 through a pipe 76, the drain pipe 63 and the return pipe 48.

When the plunger 60 of the valve 59 is moved rearwardly to open communication between the ports 61 and 62, liquid from the gear pump 55 and/or the accumulator 73 flows through the pipe 64, the pilot valve 59, the pipe 66, a duct 77, a spring check valve 78 and into the cylinder 53, causing the piston 51 to advance into the chamber 49 and move the valve plunger 38 axially to open communication between the ports 43 and 46 and to move the piston 52 into the cylinder 54, as shown in Fig. 5.

The duct 77 communicates with the outer end of the cylinder 53 through the check 78, and communicates directly with an annular port 79 which is arranged intermediate the ends of the cylinder 53.

The piston 52 and the cylinder 54 are identical, respectively, to the piston 51 and cylinder 53 and function in exactly the same manner. Consequently, like parts have been indicated by like reference numerals.

When the liquid enters the cylinder 53 and forces the piston 51 inwardly to move the valve plunger 38 and the piston 52 axially, liquid is expelled from the cylinder 54 through the duct 77, the pipe 65, the pilot valve 58 and the drain pipe 63 to the return pipe 48.

During the first part of the piston movement, the liquid flows freely from the cylinder 54 through the port 79 and into the duct 77, and the valve plunger 38 moves at high speed but, as soon as the end of the piston 52 passes the edge of the port 79, the check valve 78 causes the liquid to be expelled from the cylinder 54 through a number of tapered grooves 80 which are formed in the end of the piston 52. The effective area of the grooves 80 gradually decreases as the piston 52 moves outwardly and the plunger 38 is thus decelerated until the grooves 80 are entirely out of registry with the port 79 and the remaining liquid is trapped in the outer end of the cylinder 54, thereby bringing the plunger 38 and the pistons 51 and 52 to a complete stop without shock or impact.

The speed at which the valve plunger 38 moves is dependent upon the volume of liquid delivered to the cylinders 53 and 54 through the pipes 65 and 66 and, as the accumulator 73 provides a supply of driving liquid in excess of the requirements of the valve 9, the speed of the plunger 38 is controlled by providing pipes 65 and 66 of the correct cross-sectional area to deliver the exact volume of liquid required to move the plunger 38 at the desired speed.

After the valve 9 has been operated and its plunger 38 is in the position shown in Fig. 5,

liquid is delivered by the pump 10 through the pipe 47, the valve cylinder 39 and the duct 45 to the rear end of the motor cylinder 19, thereby forcing the piston 17 forward to advance the driving arm 6 and impart rotation to the ratchet wheel 4 and the power shaft 2.

Forward movement of the driving arm 6 moves the lower end of the lever 68 out of engagement with the stem of pilot valve 59 and allows the 10 spring 67 to move the plunger 60 to its initial position.

The liquid in the forward end of the motor cylinder 19 is expelled through a pipe 81 into the motor cylinder 18 and forces the piston 16 rearward to retrace the driving arm 5.

At the same time, the gear pump 55 is delivering an additional limited volume of liquid through the pipe 64, a pipe 82, a choke 83 and the pipe 81 into the forward end of the motor cylinder 18 to retrace the piston 16 and the driving arm 5 faster than the piston 17 and the driving arm 6 advances, and to insure that piston 16 is fully retracted and stalled against the head of cylinder 18 before piston 17 completes its working stroke.

When the driving arm 5 starts rearward, its contact face 11 disengages the bar 12 with which it was in contact and the forward end of the driving arm falls, the plunger 33 strikes the bar 12 and cushions the fall of the driving arm, and 30 then the stop 27 supports the driving arm 5 until the driving arm 6 has rotated the ratchet wheel 4 sufficiently to bring the next bar 12 into engagement with the face 35 to support the driving arm 5 as shown in Fig. 8.

The impact caused by the buffer plunger 33 striking the bar 12 causes liquid to be ejected through the restricted passageway 32 and into the reservoir 29, as previously described. When the plunger 33 moves out of engagement with the bar 12, its own weight and the pressure exerted by the spring 34 moves it downward and liquid flows into the bore 28 through the passageway 30 from the reservoir 29 which is supplied with liquid from the pipe 64 through a pipe 84 having a choke or valve 85 arranged therein to limit the flow of liquid therethrough.

When the piston 16 reaches the limit of its rearward stroke and stalls against the end of the cylinder 18, the liquid expelled from the forward end of the cylinder 19 during the remainder of the working stroke of the piston 17 passes through the pipe 81, a relief valve 86 and a pipe 87 into the drain pipe 63.

The driving arm 5 is now standing idle momentarily while the driving arm 6 rotates the ratchet wheel 4 and moves the bar 12 along the faces 35 and 36 on the driving arm 5 and into engagement with the face 11 thereon, as shown in Fig. 7, thereby enabling the forward end of the driving arm 5 to descend until the projection 70, thereon passes below the abutment 71 and the spring 69 swings the lever 68 to operate the valve 58, as previously described.

The cylinder 54 is now open to gear pump 65 pressure through the pipe 65, the valve 58 and the pipe 64, and the sudden rush of liquid from the gear pump 55 and the accumulator 73 forces the piston 52 inward at high speed to operate the valve plunger 38 and move the piston 51 into the cylinder 53 where its momentum is first checked and then the piston and plunger are brought to rest by the liquid trapped in the outer end of the cylinder 53, as explained in connection with the piston 52 and the cylinder 54.

The rapid traverse of the piston 51 causes the

liquid in the pipe 66, the valve 59, the pipe 63 and the pipe 48 to move at high speed and, when the piston 51 closes the port 79, the momentum of this liquid creates a vacuum which causes the liquid to rebound. If the check valve 72 opened freely, the rebounding liquid would enter the outer end of the cylinder 53 and force the piston 51 inward and move the valve plunger 38.

For this reason, the spring check valve 78 is adjusted to resist a pressure greater than fifteen pounds per square inch to prevent the rebounding liquid from entering the cylinder 53, thus functioning as a hydraulic detent for holding the plunger 38 in position. The other check valve 78 functions in exactly the same manner.

As the plunger 38 moves from one position to the other, the cylinders 18 and 19 are brought into communication momentarily with each other and with the pump 10, as shown in Fig. 6, by means of notches 88 which are formed in the inner faces of the pistons 40 and 41 on the plunger 38, whereby liquid from the pump 10 is delivered simultaneously to both cylinders to cause the driving arm 5 to exert force upon the ratchet wheel 4 before the driving arm 6 ceases to exert force thereon.

The motor is ordinarily operated with a liquid which is slightly elastic, such as lubricating oil, and the pressure built up by the pump 10 in advancing the piston 17 compresses the liquid and sets up stresses in the cylinder, pipes and driving arm.

When the two motor cylinders 18 and 19 are brought into communication with each other through the notches 88, the energy thus stored and particularly the expansive force stored in the large volume of liquid in the motor cylinder 19 is utilized for starting the driving arm 5 on its power stroke before the driving arm 6 ceases to apply rotative force to the wheel 4.

The volume of liquid behind the piston of the motor which is completing its working stroke, the length and depth of the notches 88 and the speed of the valve plunger 38 bear a definite relation to one another and are so proportioned that the force transmitted to the ratchet wheel by the driving arm about to be advanced increases as the force transmitted to the ratchet wheel by the other arm decreases so that a substantially uniform force is exerted at all times upon the ratchet wheel by either one or both of the driving arms.

The motors 7 and 8 are operated alternately, and the driving arm 6 is retracted in the same manner as just described. The cylinders 18 and 19 are in communication with each other and with the pump 10 at each end of each stroke of the driving arms, one or both of the driving arms are exerting force upon the wheel 4 at all times and, due to the arcuate faces 11 and 24, each driving arm is wedged between the piston rod of its motor and a bar 12 before it starts to advance. Consequently, the power shaft 2 is rotated at a uniform and constant speed.

The invention herein set forth is susceptible of various modifications and adaptations without departing from the scope thereof as hereinafter claimed.

We claim:

1. A motor, comprising a ratchet wheel, two reciprocal driving arms for engaging said wheel alternately upon the same side thereof to impart rotative force thereto, a piston and a cylinder connected to each arm for advancing and retracting it alternately with the advance and retraction of

- the other arm, means for supplying pressure liquid to the rear or pressure ends of said cylinders alternately to advance said arms alternately and cause the same to apply rotative force to said 5 wheel, means for delivering liquid to the front end of each cylinder to retract one arm as the other arm advances and to cause the retracting arm to reach the end of its return stroke before the advancing arm reaches the end of its advance stroke, 80 10 a valve included in said supplying means for directing liquid to the pressure ends of said cylinders alternately and having means for connecting said pressure ends together momentarily to cause each of said arms to apply rotative force to said wheel before the other arm ceases to apply rotative force thereto, and means for operating 15 said valve.
2. A motor, comprising a ratchet wheel, two reciprocable driving arms for engaging said wheel alternately upon the same side thereof to impart 20 rotative force thereto, a piston and a cylinder connected to each arm for advancing and retracting it alternately with the advance and retraction of the other arm, means for supplying pressure liquid to the rear or pressure ends of said cylinders alternately to advance said arms 25 alternately to cause the same to apply rotative force to said wheel, means for delivering liquid to the front end of each cylinder to retract one arm as the other arm advances and to cause the retracting arm to reach the end of its return stroke before the advancing arm reaches the end 100 30 of its advance stroke, a hydraulically operated valve included in said supplying means for directing liquid to the pressure ends of said cylinders alternately and having means for connecting said pressure ends together momentarily to cause 105 each of said arms to apply rotative force to said wheel before the other arm ceases to apply rotative force thereto, means including a pilot valve for controlling said valve, and means for operating said pilot valve.
3. A motor, comprising a ratchet wheel, two reciprocable driving arms for engaging said wheel alternately upon the same side thereof to impart 40 rotative force thereto, a piston and a cylinder connected to each arm for advancing and retracting it alternately with the advance and retraction of the other arm, means for supplying pressure liquid to the rear or pressure ends of said cylinders alternately to advance said arms 45 alternately and cause the same to apply rotative force to said wheel, means for delivering liquid to the front end of each cylinder to retract one arm as the other arm advances and to cause the retracting arm to reach the end of its return stroke before the advancing arm reaches the end 110 50 of its advance stroke, a hydraulically operated valve included in said supplying means for directing liquid to the pressure ends of said cylinders alternately and having means for connecting said pressure ends together momentarily to cause 115 each of said arms to apply rotative force to said wheel before the other arm ceases to apply rotative force thereto, means including a pilot valve for controlling said valve, and means for operating said pilot valve.
4. A motor, comprising a ratchet wheel, two reciprocable driving arms for engaging said wheel alternately upon the same side thereof to impart 55 rotative force thereto, a piston and a cylinder connected to each arm for advancing and retracting it alternately with the advance and retraction of the other arm, means for supplying pressure liquid to the rear or pressure ends of said cylinders alternately to advance said arms 60 alternately and cause the same to apply rotative force to said wheel, means for delivering liquid to the front end of each cylinder to retract one arm as the other arm advances and to cause the retracting arm to reach the end of its return stroke before the advancing arm reaches the end 120 65 of its advance stroke, a hydraulically operated valve included in said supplying means for directing liquid to the pressure ends of said cylinders alternately and having means for connecting said pressure ends together momentarily to cause each 125 of said arms to apply rotative force to said wheel before the other arm ceases to apply rotative force thereto, two pilot valves for controlling said valve, and means operated by each driving arm for operating a pilot valve.
7. A motor, comprising a ratchet wheel, two reciprocable driving arms for engaging said wheel alternately upon the same side thereof to impart 70 rotative force thereto, a piston and a cylinder connected to each arm for advancing and retracting it alternately with the advance and retraction of the other arm, means for supplying pressure liquid to the rear or pressure ends of said cylinders alternately to advance said arms 75 alternately and cause the same to apply rotative force to said 130 135 140 145 150

rotative force to said wheel, means for delivering liquid to the front end of each cylinder to retract one arm as the other arm advances and to cause the retracting arm to reach the end of its return stroke before the advancing arm reaches the end of its advance stroke, a valve included in said supplying means for directing liquid to the pressure ends of said cylinders alternately and having means for connecting said pressure ends together momentarily to cause each of said arms to apply rotative force to said wheel before the other arm ceases to apply rotative force thereto, hydraulic means for operating said valve, an accumulator connected in circuit with said hydraulic means for accelerating the operation of said control valve, and means including a pilot valve for controlling said hydraulic means.

8. A motor, comprising a ratchet wheel, two reciprocable driving arms for engaging said wheel alternately upon the same side thereof to impart rotative force thereto, a piston and a cylinder connected to each arm for advancing and retracting it alternately with the advance and retraction of the other arm, means for supplying pressure liquid to the rear or pressure ends of said cylinders alternately to advance said arms alternately and cause the same to apply rotative force to said wheel, means for delivering liquid to the front end of each cylinder to retract one arm as the other arm advances and to cause the retracting arm to reach the end of its return stroke before the advancing arm reaches the end of its advance stroke, a valve included in said supplying means for directing liquid to the pressure ends of said cylinders alternately and having means for connecting said pressure ends together momentarily to cause each of said arms to apply rotative force to said wheel before the other arm ceases to apply rotative force thereto, hydraulic means for operating said valve, an accumulator connected in circuit with said hydraulic means for accelerating the operation of said control valve, pilot valves for controlling said hydraulic means, and spring actuated means for operating said pilot valves.

9. In a hydraulic motor, the combination with a ratchet wheel, a power cylinder having its axis substantially tangential to said wheel, a piston arranged in said cylinder, means for connecting said cylinder to a source of driving liquid, means included in said connecting means for controlling the delivery of liquid from said source to said cylinder to thereby cause said piston to be reciprocated, and a driving arm reciprocated by said piston and adapted to engage the teeth of said ratchet wheel in succession and thereby impart rotation to said wheel as said arm is reciprocated, of arcuate faces on the teeth of said ratchet wheel for providing a rolling contact with said arm to raise the contact end of said arm as said wheel rotates, a stop arranged upon the contact end of said arm and overhanging a tooth of said wheel for limiting the downward movement of said arm after the contact end thereof has disengaged one of said teeth, and a buffer carried by said stop for engaging said teeth to cushion the fall of said arm.

10. In a hydraulic motor, the combination with a ratchet wheel, a power cylinder having its axis substantially tangential to said wheel, a piston arranged in said cylinder, means for connecting said cylinder to a source of driving liquid, means included in said connecting means for controlling the delivery of liquid from said source to said cylinder to thereby cause said piston to be recip-

rocated, and a driving arm reciprocated by said piston and adapted to engage the teeth of said ratchet wheel in succession and thereby impart rotation to said wheel as said arm is reciprocated, of arcuate faces on the teeth of said ratchet wheel for providing a rolling contact with said arm to raise the contact end of said arm as said wheel rotates, a stop arranged upon the contact end of said arm and overhanging a tooth of said wheel for limiting the downward movement of said arm after the contact end thereof has disengaged one of said teeth, and a hydraulic buffer carried by said stop for engaging said teeth to cushion the fall of said arm.

11. In a hydraulic motor, the combination with a ratchet wheel, a power cylinder having its axis substantially tangential to said wheel, a piston arranged in said cylinder, means for connecting said cylinder to a source of driving liquid, means included in said connecting means for controlling the delivery of liquid from said source to said cylinder to thereby cause said piston to be reciprocated, and a driving arm reciprocated by said piston and adapted to engage the teeth of said ratchet wheel in succession and thereby impart rotation to said wheel as said arm is reciprocated, of arcuate faces on the teeth of said ratchet wheel for providing a rolling contact with said arm to raise the contact end of said arm as said wheel rotates, a stop arranged upon the contact end of said arm and overhanging a tooth of said wheel for limiting the downward movement of said arm after the contact end thereof has disengaged one of said teeth, a hydraulic buffer carried by said stop for engaging said teeth to cushion the fall of said arm, a reservoir carried by said buffer for supplying the same with liquid, and means for directing liquid into said reservoir.

12. In a hydraulic motor, the combination with a ratchet wheel, a power cylinder having its axis substantially tangential to said wheel, a piston arranged in said cylinder and provided with a piston rod extending from said cylinder, means for connecting said cylinder to a source of driving liquid, means included in said connecting means for controlling the delivery of liquid from said source to said cylinder to thereby cause said piston to be reciprocated, and a driving arm connected by a lost-motion connection to said piston rod and reciprocated thereby to engage the teeth of said ratchet wheel in succession and thereby impart rotation to said wheel as said arm is reciprocated, of a bearing surface arranged upon said piston rod independent of said lost-motion connection, an arcuate face arranged upon the rear end of said arm to abut said surface and thereby take the thrust of said piston and provide a rolling contact between said arm and said piston rod, arcuate faces on the teeth of said ratchet wheel for providing a rolling contact with said arm to raise the contact end of said arm as said wheel rotates, and a stop arranged upon the contact end of said arm and overhanging a tooth of said wheel for limiting the downward movement of said arm after the contact end thereof has disengaged one of said teeth.

13. A motor, comprising a power shaft, a ratchet wheel fixed to said shaft to drive the same, two reciprocable driving arms engaging said wheel alternately to impart rotative force thereto, a piston and a cylinder connected to each arm for advancing and retracting it alternately with the advance and retraction of the other arm, means for supplying pressure liquid to the rear or pressure ends of said cylinders alternately

- to advance said arms alternately and cause the same to impart rotative force to said wheel, means for delivering liquid to the front end of each cylinder to retract one arm as the other arm advances and to cause the retracting arm to reach the end of its return stroke before the advancing arm reaches the end of its advance stroke, a control valve included in said supplying means for directing liquid to the pressure ends of said cylinders alternately and having means for connecting said pressure ends together momentarily to cause each arm to apply rotative force to said wheel before the other arm ceases to apply rotative force thereto, hydraulic means for operating said valve, means for supplying liquid to said hydraulic means and for controlling the operation thereof, an accumulator connected in circuit with said hydraulic means for accelerating the operation of said valve, and means for preventing lost motion between said piston and said ratchet wheel. 80
14. In a hydraulic motor, the combination of a ratchet wheel, a power cylinder having its axis substantially tangential to said wheel, a piston arranged in said cylinder, means for connecting said cylinder to a source of driving liquid, means for controlling the delivery of liquid from said source to said cylinder to thereby cause said piston to be reciprocated, a driving arm loosely pivoted at its rear end to said piston and reciprocated thereby to engage the teeth of said ratchet wheel in succession and thereby impart rotation to said wheel as said arm is reciprocated, an arcuate face on the rear end of said arm abutting a surface on said piston to take the thrust of said piston, arcuate faces on the teeth of said ratchet wheel for providing a rolling contact with said arm to raise the forward end thereof as said wheel rotates, a stop arranged upon the forward end of said arm and overhanging a tooth of said wheel for limiting the downward movement of said arm after its forward end has disengaged one of said teeth, and an arcuate face on the forward end of said arm for engaging a tooth of said wheel to wedge said arm rearwardly against said piston and thereby enable the arcuate face on the rear end of said arm to rock upon said surface on said piston. 100
15. A motor, comprising a ratchet wheel, two reciprocable driving arms for imparting rotative force to said wheel, a piston and a cylinder for driving each of said arms, a valve casing connected to said driving cylinders and to a source of driving liquid, a plunger arranged in said valve casing for directing driving liquid from said source to said cylinders alternately to advance and retract said pistons alternately and thereby cause said arms to impart rotative force to said wheel, hydraulic means for reciprocating said plunger, means for directing liquid to said hydraulic means to operate the same and for controlling the operation of said hydraulic means, and a hydraulic detent for preventing said plunger from being moved axially by said means. 105
16. In a hydraulic transmission having a plurality of hydraulic motors, the combination of a valve casing connected to said motors and to a source of driving liquid, a plunger arranged in said casing for controlling the delivery of liquid to said motors, a piston and a cylinder arranged at the end of said valve casing for moving said plunger axially to thereby cause liquid to be delivered to said motors alternately, hydraulic means for actuating said piston, means for directing liquid to said hydraulic means to operate the same and for controlling the operation of said hydraulic means, and a hydraulic detent for preventing said valve plunger from being moved by the rebound of said liquid after the same has been moved axially by said piston. 110
17. In a hydraulic transmission having a plurality of hydraulic motors, the combination of a valve casing connected to said motors and to a source of driving liquid, a plunger arranged in said casing for controlling the delivery of liquid to said motors, a piston and a cylinder arranged at each end of said valve casing for moving said plunger axially to thereby cause liquid to be delivered to said motors alternately, means connecting said cylinders to a source of liquid for actuating said pistons, and a spring-pressed check valve communicating with each cylinder and arranged in said means to prevent the free return of liquid to said cylinder. 115
18. The combination, with a source of driving liquid and a hydraulic motor having a hydraulically operated valve, of a cylinder having a port near its outer end and a passageway for connecting said port to said source and an auxiliary passageway connecting the inner end of said cylinder to said passageway, a piston arranged in said cylinder for operating said valve and controlling said port, means for directing liquid from said source into said cylinder to advance said piston and operate said valve, means for retracting said piston and thereby expelling liquid from said cylinder through said port until said piston closes said port, a check valve connected in said auxiliary passageway between the inner end of said cylinder and said port for admitting driving liquid above a predetermined pressure into the inner end of said cylinder and for preventing the escape of liquid from said cylinder after said port is closed, and a spring urging said check valve to its seat and preventing said expelled liquid from re-entering said cylinder and thereby serving as a detent for holding said piston in position. 120
